CLAIM

I claim the ornamental design for a gaming desk, as shown and described.

DESCRIPTION

FIG. 1 is a front perspective front view of a gaming desk, showing my new design;

FIG. 2 is a rear perspective view thereof;

FIG. 3 is a front view thereof;

FIG. 4 is a bottom view thereof;

FIG. 5 is a top view thereof;

FIG. 6 is a rear side view thereof;

FIG. 7 is a left side view thereof; and,

FIG. 8 is a right side view thereof.

The Broken lines in the drawing depict parts of the gaming desk and form no part of the claimed design.
